(57) **CLAIM**

The ornamental design for a headlight for a vehicle, as shown and described.

DESCRIPTION

This application contains subject matter related to the following co-pending U.S. design patent applications:

Application Ser. No. 29/579,113, filed Sep. 28, 2016 and entitled “Headlight for a Vehicle”;

Application Ser. No. 29/594,698, filed Feb. 22, 2017 and entitled “Headlight for a Vehicle”;

Application Ser. No. 29/605,288, filed herewith and entitled “Vehicle, Toy, and/or Replicas Thereof”;

Application Ser. No. 29/605,298, filed herewith and entitled “Headlight for a Vehicle”; and

Application Ser. No. 29/605,299, filed herewith and entitled “Headlight for a Vehicle”.

FIG. 1 is a front view of a headlight for a vehicle according to the design;

FIG. 2 is a right perspective view thereof;

FIG. 3 is a left perspective view thereof;

FIG. 4 is a right side view thereof;

FIG. 5 is a left side view thereof;

FIG. 6 is a top view thereof;

FIG. 7 is a bottom view thereof; and,

FIG. 8 is a rear view thereof.

1 Claim, 8 Drawing Sheets
